APPARATUS FOR TREATING WELLS

John J. Grebe, Midland, Mich., assignor to The Dow Chemical Company, Midland, Mich., a corporation of Michigan

Application August 28, 1940, Serial No. 354,505

7 Claims. (Cl. 166—2)

The invention relates to apparatus for treating wells, such as oil, gas, brine, or water wells. It more particularly concerns a method and apparatus whereby a fluid treating agent may be simultaneously introduced into two or more zones penetrated by the bore of a well while said zones are sealed off or separated from one another in such a manner that the fluid treating agent in the well bore about to enter one zone is maintained out of contact with the fluid entering the other zone.

The bore of a well oftentimes penetrates more than one producing section or zone, and it is usually desirable when treating such wells with a fluid treating agent to be assured that some of the agent will be injected into each section. In some instances it is even desirable to closely control the amount of agent that is injected into each zone. For example, in the treatment of more than one productive zone in calcareous earth or rock to bring about an increase in production by use of an agent such as acid, it is usually desirable that a method of treatment be provided to positively insure that each zone will receive a proportionate quantity of the acid, for otherwise substantially all the acid may drain into the zone having the most porous structure with the result that little or no increase in production will be obtained from the zone or section having the smaller pore spaces or voids. It is further desirable when treating such wells that the introduction of the fluid agent into each zone take place simultaneously in order to avoid the necessity of carrying out a separate treatment of each zone.

The term "zone," used herein and in the appended claims, refers to separately defined strata as well as sections of a single formation or stratum.

It is, therefore, the principal object of the invention to provide apparatus whereby a fluid treating agent may be simultaneously introduced into each of at least two zones penetrated by the bore of a well.

Another object of the invention is to provide an apparatus useful in connection with the simultaneous introduction of an acid or other treating fluid into at least two zones penetrated by the bore of a well, which will automatically regulate any pre-selected ratio of rates of flow at any time during the treatment in such a manner that the rate of flow to the zone which requires the application of the least pressure to force fluid thereinto at a previously selected rate is de-

creased in an amount directly proportional to the difference in pressure required.

Still another object is to provide an apparatus which may be used for the simultaneous injection of a fluid agent into at least two zones and for separately testing the productivity of each zone either before or after the injection of the fluid agent.

Other objects and advantages will be apparent as the description of the invention proceeds.

The invention then resides in the apparatus hereinafter more fully described and particularly pointed out in the claims, the accompanying drawings and following description setting forth in detail apparatus for carrying out the invention, such mode illustrating, however, but one of several ways in which the invention may be put into operation.

In the accompanying drawings:

20 Fig. 1 is a fragmentary view of a well bore in vertical cross-section showing one embodiment of the invention.

25 Fig. 2 is a fragmentary sectional view of Fig. 1 showing that section of conduit 9 which includes the discharge orifice 12, and illustrates additional elements associated with the orifice which act to modify the action of said discharge orifice.

30 Fig. 3 is an elevational view of a well bore showing a modification of the apparatus illustrated in Fig. 1 wherein said apparatus is shown adapted for use in treating more than two zones or sections.

35 Fig. 4 is a fragmentary cross-sectional view of a well bore showing another embodiment of the invention comprising a flow control element adapted for use in connection with the simultaneous introduction of a fluid treating agent into each of two or more zones which at the same time alters a pre-selected ratio of rates of flow into each zone at any time during the treatment so as to decrease the rate of flow of the fluid agent to the zone into which the fluid agent flows at the lowest applied pressure.

40 Referring more in detail to Fig. 1, the upper portion 1 of the well bore is shown cased with metal pipe 2 down to a point 3 where it is cemented in place by cement 4. The lower portion 5 of the well bore penetrates productive stratum 6, an impervious stratum 7, and ends in a second productive stratum 8. Attached to well tubing (not shown) conduit 9 extends into the well through the casing 2 and is shown provided with a threaded boss 10 at a point adjacent productive stratum 6. A bushing 11 threadedly en-

gages the boss 10 and is provided with an orifice 12 through which fluid may issue from the conduit 9 into the well bore. Attached to the conduit 9 at a point below boss 10 is a packing element 13 of conventional design, shown in a seated position so as to seal the annular space between the conduit 9 and the well bore at a point intermediate the productive strata 6 and 8. A second conduit 14 is attached to the lower end of the packing element 13 and communicates with conduit 9 through packing element 13. Engaging threaded boss 15 in conduit 14 is a bushing 16, which is provided with an orifice 17 through which fluid may issue from the interior of the conduit 14 into the well bore at a point below the packing element 13 so as to contact productive stratum 8. The lower end of conduit 14 is provided with a cap member 18 of conventional design adapted to prevent egress of fluid from the lower end of the conduit 14. The portion of the well bore below the packing element 13, as well as the conduit 14, is shown filled with treating fluid 19, while the well bore exteriorly of the packing element above said element is also filled with treating fluid 19 up to a point 3 adjacent the upper level of productive stratum 6. The remaining portion of the annular space between the well bore and conduit 9 is shown filled with oil 20, which acts as a pressuring fluid and also controls the level to which the treating liquid rises in the well bore during a treatment. The treating fluid is also shown filling the interior of the conduit 9.

In the fragmentary sectional view shown in Fig. 2, the orifice 12 of Fig. 1 is shown equipped with a back pressure valve assembly. The housing 21 of the valve assembly is shown attached to conduit 9 adjacent orifice 12, as by means of a weld. The valve assembly consists of a ported housing 21 having a well 23 in which valve stem 24 slides as pressure applied interiorly of the conduit 9 overcomes the pressure of spring 22 acting to force the valve into sealing relationship against orifice 12 provided in conduit 9.

In Fig. 3 the apparatus of Fig. 1 is shown adapted for use in simultaneously introducing a treating fluid into more than two zones or strata. As shown, spaced productive strata 25, 26 and 27 are separated by impervious strata 28 and 29. The productive strata or zones are shown sealed from each other by packing elements 13, such as shown in Fig. 1, seated against the impervious strata. Conduits 30, 31 and 32 attached to the packing elements 13 communicate with each other through the packing elements, and are provided with ports 33, 34 and 35, respectively, which may be varied in size as desired and through which fluid may enter the well bore and contact the productive zones while said zones or strata are separated from each other.

The fragmentary sectional view shown in Fig. 4 illustrates a structure which may be employed according to the invention to simultaneously introduce a treating fluid into two zones while said zones are sealed from each other in such a manner that the fluid entering one zone is maintained out of contact with the fluid entering the other zone. Further, the apparatus is adapted to exercise control over the rate of flow of fluid entering each zone or stratum so as to insure that the pre-selected ratio of rates of flow of the treating fluid will be automatically regulated, so as to decrease the rate of flow of fluid to that stratum or zone requiring the application of the

lowest pressure to introduce fluid thereinto at the selected rate.

In addition, the apparatus may be employed in connection with accurately ascertaining the productivity of each zone before or after treatment with a fluid agent has been accomplished, and to test the packing element as regards the effectiveness of the seal being obtained between the two zones. As shown, well casing 2 extends into the well bore to a point above productive stratum 6 and is cemented off in the manner shown in Fig. 1. Conduit 36, adapted to be attached to the conventional well tubing (not shown), extends into the well and engages tubular member 37 in sliding sealing relation. The tubular member 37 is attached at its lower end to the packing element 38, which is shown in seated engagement with non-productive stratum 7. A slot 39 extends transversely of the tubular member 37 and is provided at both ends and in the middle with depressions for locking engagement with a lug 40 attached to conduit 36. The slot and lug are so arranged that as the lug engages the depression at the extreme right of the slot, port 41 in conduit 36 registers with port 42 in the tubular member 37, while if the conduit 38 is raised and rotated so that lug 40 engages the depression at the extreme left of the slot, port 41 in conduit 36 engages port 43 in tubular member 37. The lug 40 may also be caused to seat in the depression in the middle of the transverse slot 39, in which case port 41 in conduit 36 will not be in registry with either port 42 or 43, thus preventing flow of fluid to and from conduit 36 at a point above the packer 38. The conduit 36 extends into the central portion of the packing element 38 and ends in an inwardly projecting flange 44. The flange 44 acts as a seat for the body member 45 housing the control element, which is adapted to regulate the flow of fluid into the zones above and below the packer. The body 45 of the control element is held in position on the inwardly projecting flange 44 of the conduit by means of bolts 46 which engage a flange 47 of the body member. The body 45 of the control element is in two sections secured to each other at flanges 48 by means of screws 49. The interior of the body of the control element is divided into two compartments by means of a diaphragm 50, which is secured to the body member of the control element by screws 49 at flanges 48. The diaphragm is of corrugated or bellows-like construction and is thus adapted to move laterally in either direction as pressure in one compartment builds up in excess of that in the other compartment. The diaphragm is provided on either face with centrally located tapered plug members 51, which are adapted to engage ports or orifices 52 and 53 in the body member 45 so as to partly seal off or regulate the flow of fluid into either compartment as the diaphragm 50 moves back and forth. The tapered plug members 51 are also adapted to engage springs 54 surrounding the orifices 52 and 53 as the plug members 51 are caused to move over and partially seal the orifices 52 and 53. The springs 54 act to urge the diaphragm 50 back on center and are of such length that when completely compressed they prevent the plug member 51 from completely sealing off or closing the orifices. The compartment on the right side of the diaphragm 50 communicates with port 41 in conduit 36 by means of a tube 55, thus allowing fluid to escape from the interior of the control element into the stratum above the packer. The compartment on

the left side of the diaphragm communicates through tube 56 with the space below the packer and allows the treating fluid to enter the formation below the packer. The lower end of conduit 36 is provided on its outer surface with lugs 57, which engage a longitudinal slot or narrow groove 58 in tubular member 59, and serve as a means whereby the packer may be seated or released by raising and lowering conduit 36. Below the packer body, tubular member 59 passes through a sleeve member 60, which it engages in sliding sealing relation, and ends in an outwardly projecting flange 61. This flange engages a corresponding flange 62 of element 63. Element 63 ends in cap member 64, which bears against the bottom of the well bore. The tubular member 59 is provided with a port 65, which is shown in registration with port 66 in the sleeve member 60. The tubular member 59 is also provided with lug 67, which engages a slotted track in sleeve 60 so as to allow the tubular member 59 to rotate in sleeve 60, thus bringing port 65 into registration with the second port 68 in sleeve 60. Port 68 is so located that as conduit 36 is raised and rotated through 90°, or until lug 40 engages the depression centrally located in the transverse slot 39, port 65 then registers with port 68 in sleeve member 60. Flanges 61 and 62 are secured together by means of bolts 69 passing through slotted holes 70 in said flanges. This arrangement allows the conduit 36 and tubular member 59 to turn as a unit, and the ease of turning is facilitated by the fact that flange 61 can turn on flange 62 while element 63 remains stationary.

The method of the invention will be best understood from the following description wherein the apparatus illustrated in Fig. 1 is employed to carry out an acid treatment for the simultaneous injection of acid into two separately defined strata. With the apparatus assembled as shown, conduit 9 attached to the well tubing (not shown) is lowered into the well bore so as to position the packing element adjacent the impervious stratum 1. The packer is then seated so as to separate productive stratum 6 from productive stratum 8, and a quantity of acid is introduced into the well through the well tubing in communication with the conduit 9. Pressure is then applied to the acid, as by pumping an additional quantity of acid into the well through the well tubing. At the same time oil is introduced into the annular space exterior of the well tubing and the conduit 9 so as to control the level to which the acid solution can rise in the well bore as it escapes from the upper port or orifice 12. Acid is caused to discharge from orifice 12 as well as from orifice 17 and enters both productive strata simultaneously. The orifices 12 and 17 in bushings 11 and 16 are conveniently chosen of such size that there will always be a pressure drop between the interior of conduit 9 and the well bore, as pressure is applied to cause the treating fluid to discharge from the conduit. By varying the diameter of the orifices, more or less acid can be forced into a selected zone. By selecting the orifices of such size that a higher pressure can be maintained interiorly of the conduit than exteriorly thereof, and varying the size of the orifice adjacent each zone, the amount of acid entering each zone is susceptible of control, and, at the same time, assurance is had that some acid is entering each zone if such are not entirely impervious.

It is highly desirable to introduce the treat-

ing fluid at such a rate that a pressure drop is maintained across the orifices or restricted openings comparable to the pressure being employed to force the fluid into the zone or stratum having the highest resistance to the flow of the treating agent. The information required in order that a treatment be carried out in this manner may be obtained by testing the formations before the actual treatment is carried out or, in some cases, it may be already recorded for the particular oil field or geographical location in question. Treating under such conditions insures that the apparatus will act to most effectively regulate the treating fluid. After the desired quantity of acid has been introduced, it may be displaced from the interior of the well tubing and conduit 9 by pumping a quantity of oil or the like into the well through said tubing.

The simultaneous introduction of the fluid agent above and below the packing element has the important advantage that the pressure applied on one side of the packing element to introduce the fluid agent acts to balance the pressure on the other side so that the differential pressure across the packer is low, thus substantially eliminating any danger of a leak occurring around the packer or of the packer blowing out due to having a high pressure applied on but one side. After a sufficient amount of time has been allowed to elapse for the treating solution to react with the formation, it may be withdrawn from the well, as by a swabbing operation. The apparatus may then be withdrawn and the well put into production.

It is to be understood that the method is applicable wherein it is desired to treat any desired number of spaced productive zones by sealing them from one another in the manner shown in Fig. 3 using a plurality of packers to separate each stratum and wherein one or more orifices of the desired size communicate with each stratum.

It is also to be understood that the spring loaded back pressure valve assembly shown associated with the discharge orifice of the apparatus illustrated in Fig. 2 may be employed in conjunction with the orifices, restricted openings, or the fluid outlet ports of the apparatus illustrated in Fig. 4. The back pressure valve or orifices, associated with the discharge ports or orifices, may be advantageously employed in some instances, as for example to compensate for differences in formation pressure existing in various zones so that an orifice may be selected to give the desired flow against the back pressure of the valve, thus eliminating the necessity of taking the formation pressure into consideration when selecting an orifice to give a desired rate of flow at various pressures. In this manner the rate of flow at various applied pressures is more nearly dependent upon exact orifice size.

The method of the invention may also be suitably carried out employing the apparatus illustrated in Fig. 4, which is adapted to automatically decrease the rate of flow of fluid, e. g., acid, flowing into either stratum at any time during the treatment so as to direct a smaller rate of flow of acid to the stratum requiring the application of the least pressure to force the acid thereinto. The decreased rate of flow of acid entering the stratum requiring the application of the least pressure to force fluid thereinto is directly proportional to the diminution in pressure required to force the fluid thereinto. It is usually highly desirable in carrying out an acid treatment that the rate of introduction be con-

trolled in the above manner because it oftentimes happens that one zone or stratum has a relatively low permeability to the flow of fluids and thus the desired fluid agent is prevented from gaining access to that stratum readily. In such cases it is therefore desirable that the rate of flow of the treating fluid be decreased to the one zone so that a relatively greater amount is directed into the more impervious stratum in order to bring about a relatively greater increase in permeability. The apparatus, assembled as shown in Fig. 4, is positioned in the well bore with ports 41 and 42 above the seated packer and ports 65 and 66 below the packer in registry. A quantity of acid is then introduced into the well through the tubing (not shown), which is in communication with conduit 36. The acid flows downwardly into the body member 45 of the control element through orifices 52 and 53 provided therein. The fluid entering the left compartment escapes through tube 56 and thereafter through ports 65 and 66 and enters the lowermost zone or stratum 8. The fluid entering the right compartment discharges through tube 55 and ports 41 and 42 and enters the formation above the packer. If desired, a quantity of oil or other pressuring fluid (not shown) may be introduced into the annular space between the well casing and the conduit 36 to control the level to which the treating fluid rises in the well bore. If for any reason the fluid does not readily enter one formation, pressure builds up in the compartment of the control element communicating with the formation which the fluid is not entering readily and causes the diaphragm 50 to move in a direction to relieve the pressure, thus actuating the plug members 51 so as to partially seal the orifice communicating with the compartment into which fluid is rapidly entering and discharging. This sealing action automatically continues as long as a higher pressure is needed to force the acid into the one stratum. Thereafter the plug members 51, aided by spring 54, tend to assume a central location in the control element so as to allow acid to enter either compartment readily and flow therefrom into each stratum until for some reason the fluid does not readily enter one stratum. When this occurs, the plug members 51 again automatically curtail the flow of fluid into the stratum readily taking fluid so that as the treatment continues each stratum receives a more desirable quantity of the treating agent. In the foregoing manner, the productive stratum which requires the application of the lowest pressure to force the fluid treating agent thereto will be assured of having the rate of flow of fluid agent thereto curtailed, which is desirable inasmuch as the highest rate of flow of the desired treating fluid should generally be to the stratum or strata having the highest resistance to the flow of fluids thereto.

It will be readily apparent that the volume of the treating agent entering either stratum may be further controlled to some extent by selecting larger or smaller orifices. For example, the extent or thickness of each stratum is usually known prior to a treatment, and in such cases orifices may be selected which will allow the fluid treating agent to flow therethrough in an amount roughly proportional to the extent or thickness of the formation.

After the desired amount of acid has been introduced into each stratum it may be desirable to ascertain the increase in the productivity of each stratum and the apparatus illustrated in

Fig. 4 is adapted for use in making such a measurement. If it is first desired to test the productivity of lower stratum 8, while the flow of fluid from stratum 6 is sealed off, conduit 36 is lifted so that lug 40 is free to move in the transverse slot 39 in conduit 37. Conduit 36 is rotated through 90° or until the lug 40 engages the depression centrally located in the transverse slot 39. At this time port 65 in the tubular member 59 will be in registry with port 68 in element 60, allowing fluid to flow into the interior of the assembly from stratum 8. At this time port 41 in conduit 36 will be sealed against tubular member 37, preventing fluid from flowing into the interior of the assembly from productive stratum 6. The well may be allowed to flow, and since the upper formation 6 is sealed so that fluid cannot enter conduit 36, an accurate production test on stratum 8 can be made. Thereafter a production test of stratum 6 is made while fluid entry into conduit 59 from stratum 8 is prevented. This is accomplished by raising conduit 36 slightly so that lug 40 disengages the depression in the center of the transverse slot 39. The conduit 36 is then rotated so that the lug 40 engages the depression at the extreme left of transverse slot 39, at which time port 41 will register with port 43 in the tubular member 37, while port 65 below the packing element will be sealed against the sleeve member 60. Thereafter the well may be allowed to flow and thus the productivity of stratum 6 is ascertained while fluid entry from stratum 8 is prevented. In the same manner the apparatus may be employed to test the flow of fluids before a treatment has been carried out. Similarly the effectiveness of the seal produced by the packer may be tested by attempting to circulate a fluid such as oil around the packer. This may be accomplished by pumping the oil or the like into the well through conduit 36 and into the well bore below the packer while conduit 36 is not in communication with the well bore above the packer, or by sealing off the conduit 36 from the well bore above the packer and pumping the oil down into the annular space between the well bore and conduit 36 while allowing any of the oil passing around the packer to enter the tubular member 59 below the packer. In either case, if fluid can be forced around the packer, the packer may be reseated to give a more effective seal.

The method will be found to have most general use in connection with an acid treatment wherein a solution of hydrochloric or other acid is introduced into the formation to bring about an increase in size of the flow channels through which the desired mineral fluid flows to the well. In such treatments it will usually be found preferable to employ an aqueous solution of hydrochloric acid of from 5 to 25 per cent concentration. If desired, such an acid may be inhibited against corrosive attack upon iron or steel in the manner taught in U. S. Patent No. 1,877,504.

Although the method has been described with particular reference to an acid treatment, it is to be understood that any fluid treating agent may be introduced in accordance with the method of the invention. Examples of such treating agents are paraffin solvents, liquid sealing agents, and the like.

In the above manner a fluid treating agent, such as an acid, may be simultaneously introduced into two or more strata or zones with the assurance that each formation will receive a

more satisfactory treatment than is the case if the conventional method is employed wherein the bore hole is merely filled with the treating fluid and pressure is applied thereto whereby the treating fluid is directed indiscriminately to each stratum.

I claim:

1. In a well treating device for the simultaneous introduction of a fluid agent into at least two zones penetrated by the bore of a well, the combination of a conduit having spaced openings therein, sealing means surrounding said conduit adapted to seal the annular space between the conduit and the well bore at a point between the openings, a control element sealed in said conduit having ports for the entry of fluid into the interior thereof and fluid exit ports communicating respectively with the spaced openings above and below the sealing means, and a movable member dividing and sealing the interior of the control element into two compartments so that a fluid entry port and a fluid exit port communicate with each compartment, said movable member being adapted to engage the fluid entry ports in partial sealing relationship as the movable member is caused to move by pressure building up in one compartment in excess of that in the other compartment.

2. In a well treating device for the simultaneous injection of a fluid agent into at least two zones penetrated by the bore of a well, the combination including a conduit having spaced openings therein, sealing means surrounding said conduit adapted to seal the annular space between the conduit and the well bore at a point between the said openings, a control element sealed in said conduit having ports for entry of fluid into the interior thereof, and fluid exit ports communicating respectively with the spaced openings above and below the sealing means, a movable diaphragm member dividing the interior of the control element into two compartments so that a fluid entry port and a fluid exit port communicate with each compartment, and a plug member carried by the movable diaphragm adapted to engage the fluid entry ports in partial sealing relationship as the diaphragm is caused to move laterally by pressure building up in one compartment in excess of that in the other compartment.

3. The apparatus of claim 2 wherein a spring loaded back pressure valve is associated with one of the fluid exit ports.

4. In a well treating device for the simultaneous injection of a fluid agent into at least two zones penetrated by the bore of a well, the combination of a conduit having spaced openings therein, sealing means surrounding said conduit adapted to seal the annular space between the conduit and the well bore at a point between said openings, a control element sealed in said conduit having ports for entry of fluid into the interior thereof and fluid exit ports communicating respectively with the spaced openings above and below the sealing means, a movable member dividing the interior of the control element into two compartments so that a fluid entry port and

fluid exit port communicate with each compartment, a plug member carried by the movable member adapted to engage the fluid entry ports in partial sealing relationship as the movable member is caused to move laterally by pressure building up in one compartment in excess of that in the other compartment, and springs associated with the fluid entry ports adapted to engage the plug member as it moves laterally to prevent complete sealing of the fluid entry ports.

5. In a well treating device for the simultaneous injection of fluid agent into at least two zones penetrated by the bore of a well, the combination including a conduit having spaced openings therein, sealing means surrounding said conduit adapted to seal the annular space between the conduit and the well bore at a point between the openings, a control element sealed in said conduit having ports for entry of fluid into the interior thereof and fluid exit ports communicating respectively with the spaced openings above and below the sealing means, said fluid entry ports having a diameter which is proportional to the thickness of the zones with which they communicate, a movable diaphragm member dividing the interior of the control element into two compartments so that a fluid entry port and a fluid exit port communicate with each compartment, and a plug member carried by the movable diaphragm adapted to engage the fluid entry ports in partial sealing relationship as the diaphragm is caused to move in the compartment.

6. In a well treating device for the simultaneous introduction of a fluid agent into at least two zones penetrated by the bore of a well, the combination of a conduit having spaced openings therein, sealing means surrounding said conduit adapted to seal the annular space between the conduit and the well bore at a point between the openings, a control element comprising a housing sealed in said conduit and having ports for the entry of fluid from within the conduit into the interior thereof and fluid exit ports each communicating with one of the entry ports and with one of the spaced openings and mechanism within said housing whereby the fluid flowing to one of said exit ports operates to control the flow of fluid through the other.

7. In a well treating device for the simultaneous introduction of a fluid agent into at least two zones penetrated by the bore of a well, the combination of a conduit having spaced openings therein, sealing means surrounding said conduit adapted to seal the annular space between the conduit and the well bore at a point between the openings, a control element sealed in said conduit having a movable member therein dividing the interior thereof into two compartments each having an entry port to admit fluid from the conduit and an exit port communicating with one of the above mentioned spaced openings, said movable member being adapted to be moved by fluid pressure on either side thereof to restrict flow of fluid between the entry and exit ports on the opposite side.

JOHN J. GREBE.
